UNITED STATES PATENT OFFICE.

JOHN C. FREDRICKSEN, OF MILLER, INDIANA.

CARBURETOR.

Application filed September 3, 1921. Serial No. 498,241.

To all whom it may concern:

Be it known that I, JOHN C. FREDRICKSEN, a citizen of the United States, and a resident of the city of Miller, county of Lake, and State of Indiana, have invented certain new and useful Improvements in Carburetors, of which the following is a specification.

My invention relates to new and useful improvements in carburetors adapted for use in conjunction with internal combustion engines, and has for its main object the provision of a carburetor which is constructed of a minimum of parts, is economical to manufacture, is easily assembled and not apt to get out of order, and, at the same time is highly efficient in use.

Another object is to provide a carburetor with setting means which will admit a slight amount of fuel when the valves are in the closed position and will keep the engine running slowly to prevent shutting off the engine altogether, and thus provide a constant speedy starting.

Other objects will appear hereinafter.

The invention consists in the combinations and arrangements of parts hereinafter described and claimed.

The invention will be best understood by reference to the accompanying drawings forming a part of this specification, and in which,—

Fig. 1 is a fragmentary side elevation of an automobile, showing my carburetor connected to the intake manifold of the automobile engine,

Fig. 2 is a vertical section taken on line 2—2 of Fig. 1,

Fig. 3 is a plan view of the carburetor, the float chamber cover being partly broken away,

Fig. 4 is a cross section taken on line 4—4 of Fig. 2,

Fig. 5 is a vertical section on line 5—5 of Fig. 3,

Fig. 6 is a perspective view of the cylindrical throttle member,

Fig. 7 is a cross section taken on line 7—7 of Fig. 2, showing the fuel regulating valve in substantially closed position,

Fig. 8 is a cross section taken on the same line as Fig. 7 but showing the regulating valve in open position, and

Fig. 9 is a cross section taken on line 9—9 of Fig. 2.

I have illustrated my improved carburetor 11 as provided with an upper flange 14, which is secured by means of suitable securing elements to a flange 15 on the intake manifold 12 of the engine of an automobile 13. The carburetor is, however, adapted to be connected to the intake manifold of any internal combustion engine, and in any suitable manner. The material of which the carburetor is constructed may be brass or any suitable metal.

In the usual carburetors now on the market the gasoline or liquid fuel particles are mixed with the air in a special mixing chamber and then the mixture of fuel and air passes the usual throttle valve, the admission of the fuel and of the air being usually controlled by special valves, separate from the throttle valve, which valves are operated by manual means apart from the throttle lever. In my carburetor the liquid fuel particles and air come together and commingle immediately above the throttle, and no additional fuel control valve and air control valve are required besides the throttle valve. The same lever controls the admission of fuel and air and the admission of this mixture to the intake manifold.

The carburetor 11 includes the usual liquid fuel chamber or float chamber 16 provided with a feed pipe 17 connecting the usual supply tank (not shown) with the float chamber through the hollow stem 18. A fuel supply valve in the form of a needle valve 19 is provided to control the inner end of said hollow stem, said valve having a universal joint connection with one end of a lever 20 which is pivoted on a rod 21 supported in the walls of said chamber. The free end of said lever is fastened to a float 22 which controls the valve and inflow of fuel to the float chamber, in the usual manner, and a suitable cover 23 is provided for the float chamber.

A cylindrical chamber or casing 25 is constructed integral with one side wall of the float chamber 16, extending at an inclination along said wall and being closed at the bottom and open at the top, as best shown in Fig. 2. A neck or pipe 26 extends laterally

from the upper end of said chamber or casing, providing an air intake or conduit 27, and a small opening 28 is provided in the wall at the lower end of the chamber, connecting the interior of the float chamber 16 with a slight recess 29 formed in the interior wall of the chamber 25, as best shown in Figs. 2 and 9, said recess being substantially rectangular and about one-eighth of an inch 10 in depth.

The means for controlling the admission of air and fuel consists of a throttle valve or member 30 in the form of a cylindrical brass tube closed at both ends, and fitting snugly within the cylindrical chamber or casing 25, in which it is rotatably mounted. An air inlet or opening 31 is provided at the side of the tubular member 30, adjacent the upper end, registerable with the 15 intake opening 27 of the casing, and a semi-circular or D-shaped opening 32 is provided in the side of the tubular member 30, adjacent the lower end thereof. A slight recess 33 is formed on the periphery of said member 30, leading from said opening 32 and extending partially around said member 30, said recess being only about 1/64 of an inch in depth. A pipe 34 is formed integral with the chamber 25 and extends to 20 the securing flange 14. Said pipe communicates with the interior of the chamber through an opening 34' and forms the passage for the fuel and air mixture from the chamber to the intake manifold 12. An 25 operating arm 35 is fastened to the upper end of the throttle member 30 in any suitable manner, and an operating link 36 leads from the free end of said arm to a suitable operating member. A set screw 37 is 30 threaded in the wall of the chamber or casing 25, and extends into said chamber or casing, its inner end engaging in a slot 38 provided in the tubular member 30, to limit the rotational movement of said member 35 in the chamber 25.

In use the gasoline flows from the float chamber 16 through the small opening 28 into the lower end of the chamber 25, passing through the recess 29, formed on the 30 interior of the casing, into the recess 33 and stands up to and adjacent the opening 34' in the wall of the chamber. Under conditions of rest the air passes through the intake 35 27, inlet 31, tubular member 30, D-shaped opening 32, and recess 33 into the opening 34' and pipe 34, as best seen in Figs. 2 and 7, and while the valve member is set in this position of rest, a slight amount of air mingles in substantially equal quantities with a slight amount of fuel admitted from the recess 29 through the corner point of the recess 33, thus forming a small quantity of rich gas mixture, which is kept present in the intake manifold, and by reason of which the engine is kept running 60 65

very slowly to avoid complete shutting off and to leave the engine at all times ready to be started immediately, and without the aid of any priming thereto or especial priming means. To change the device to running condition the arm 35 and throttle member 30 are turned clockwise as viewed in Figs. 2, 4 and 6, and anti-clockwise as viewed in Figs. 7 and 8, thereby moving the recess 33 over the recess 29, and increasing the overlapping portions of said recess, thereby admitting a larger amount of gasoline or liquid fuel to enter the recess 33 and a larger amount of fuel to be drawn with the air through the pipe 34 into the manifold. During this running position the air is admitted from the throttle member 30 directly through the opening 32 therein, and through the opening 34' of the chamber 25, there to mingle with the gasoline or fuel 80 in proportionately larger quantities in order to provide a proper fuel mixture, one not nearly as rich as the mixture present in the pipe 34 while the engine is at rest.

With the above construction I have provided a carburetor which dispenses with the separate air, fuel, and throttle valves and the levers therefor, and have provided a structure which is simple and fool proof, which controls the admission of air and fuel by turning a single throttle member by means of a single lever, and I have produced a device which does not make use of numerous complicated members but only a few elements which act positively and which will always produce a proper fuel mixture.

While I have illustrated and described the preferred form of construction for carrying my invention into effect, this is capable of variation and modification without departing from the spirit of the invention. I, therefore, do not wish to be limited to the precise details of the construction set forth, but desire to avail myself of such variations and modifications as come within the scope of the appended claim.

Having described my invention, what I claim as new and desire to secure by Letters Patent, is:—

In a carburetor for an internal combustion engine, a fuel chamber, a cylindrical member formed integral with the wall of said chamber, a fuel inlet provided through said wall from said chamber to said member, a recess at the inner side of said member and communicating with said inlet, a tubular valve with closed ends rotatably mounted in said member, a recess angularly disposed relative to the recess on said cylindrical member formed on the periphery of said valve and having a corner in constant communication with the recess on said member, a discharge conduit leading from said member and in constant communication with said peripheral recess, an air inlet on

said member, an opening through said valve being in constant communication with said air inlet, and an opening through said valve admitting air from the interior of said valve through said peripheral recess to said discharge conduit when the valve is in closed position.

In testimony whereof I have signed my name to this specification in the presence of two subscribing witnesses.

JOHN C. FREDRICKSEN.
